UNITED STATES PATENT OFFICE.

EDWIN B. THORBURN, OF HIGHTSTOWN, NEW JERSEY.

GOVERNOR FOR STEAM-ENGINES.

SPECIFICATION forming part of Letters Patent No. 612,443, dated October 18, 1898.

Application filed June 1, 1897. Serial No. 639,022. (No model.)

To all whom it may concern:

Be it known that I, EDWIN B. THORBURN, a citizen of the United States, residing at Hightstown, in the county of Mercer and State 5 of New Jersey, have invented certain new and useful Improvements in Governors for Steam-Engines, of which the following is a full and complete specification, such as will enable those skilled in the art to which it applies 10 to make and use the same.

This invention relates to governors for marine and other steam engines; and the object thereof is to provide an improved device of this class by means of which the speed of the 15 engine may be regulated at all times regardless of the condition under which it is operated and which is adapted to prevent variation in the operation thereof, which is frequently occasioned by the rolling of the vessel in rough weather, and in which these 20 and other desired objects are accomplished by means of air-pressure, as hereinafter described.

The invention is fully disclosed in the following specification, of which the accompanying drawings form a part, in which the separate parts of my improvement are designated by the same numerals of reference in each of the views, and in which—

Figure 1 is a sectional side view of my improved governor, and Fig. 2 a section on the line 2 2.

In the drawings forming part of this specification, reference being made to Fig. 2, I have shown at 5 a steam-pipe by means of which steam is conveyed to the cylinder of the engine, and said pipe is composed of two sections which are provided at their ends with flanges or rims 6, and in the practice of my invention I provide a governor in which I employ a casing 7, which is preferably cylindrical in form and which is bolted between the flanges or rims 6. The casing 7 is open at one side, as shown at 8, and the opposite side thereof is provided with transverse slots or openings 9, and mounted in said casing is a valve 10, which is oblong in form and which is adapted to slide between the side walls of the opening 8, and said valve is provided with 45 transverse openings 11, and connected with the lower end of the valve 10 is a valve-rod 12, which passes downwardly through a tubu-

lar extension 13, formed on the lower side of the casing 7, and through a packing-box 14, and secured to the casing 7 are two downwardly-directed screw-threaded parallel rods 15, to the lower ends of which is secured a cylinder 16, in which is mounted a piston 17, with which the valve-rod 12 is connected.

Mounted on the screw-threaded parallel rods 15 is a cross-bar 18, which is provided with a central hub 19, through which the valve-rod 12 passes, and the ends of the cross-bar 18 are provided with tubular heads 20, in which are mounted nuts 21, through which the rods 15 pass, and by manipulating the nuts 21 the cross-rods 18 may be raised or lowered on said rods 15, and between the piston 17 and the central hub 19 of the cross-rod 18 is a spiral spring 22.

Formed in the walls of the cylinder 16 is an annular chamber 23, and communicating with said chamber are pipes 24 and 25, and in practice water is forced through one of said pipes into said chamber under pressure 75 and leaves said chamber through the opposite pipe, the object of thus circulating the water through the annular chamber 22 being to keep the cylinder 16 cool at all times.

Communicating with the cylinder 16, near the lower end thereof, is an air-pipe 26, and on the opposite side of said cylinder and adjacent to the lower end thereof is secured a tubular casing 27, the outer end of which is closed by a screw-threaded plug 28, and the interior of said casing is in communication with the lower end of the cylinder 16 by means of a small port or passage 29, and said casing is provided adjacent to its inner end with ports or passages 30, which open outwardly, and passing through the screw-threaded plug 28 of the casing 27 is a valve-rod 31, the inner end of which is provided with a valve 32, which is adapted to close the port or passage 29, and between the valve 32 and the end of the plug 28 is a spring 33, which operates to force the valve 32 inwardly, so as to close the port or passage 29, and the pressure on the valve 32 may be regulated as desired by means of the screw-threaded plug 28.

The lower end of the cylinder 16 is closed by a cylindrical plug 34, which is provided with a downwardly-directed valve-casing 35, and said valve-casing is provided with a

2 downwardly-directed extension 36, and passing centrally through the plug 34 and the valve-casing 35 and the downwardly-directed extension 36 thereof is a longitudinal bore or 5 passage 37, and mounted in the valve-casing 35 is a valve 38, which is adapted to close the port or passage 37, and secured to the valve-casing 35 is a quadrant-shaped plate 39, in which is formed a segmental or circular slot 10, and the valve 38 is provided with a lever 41, which is provided with a set-screw 42, which passes through the slot 40, whereby the lever 41 may be locked in any desired position.

15 The piston 17 may be of any desired form or construction, and the valve-rod 12 passes loosely through the hub 19 of the cross-rod 18, and by means of said cross-rod the pressure of the spring 22 on the piston 17 may be 20 regulated as desired, the object of this spring being to normally hold the piston 17 adjacent to the bottom of the cylinder 6 or in such position that it will not close the passage through the pipe 26 and the port or passage 29, and in 25 practice the pipe 26 is connected with an air-pump, and the operation will be readily understood from the foregoing description when taken in connection with the accompanying drawings and the following statement thereof.

30 In the normal position of the parts the piston 17 is at the lowest point of its movement in the cylinder 16 and the steam is free to pass through the valve-casing 7, and when it is desired to run the engine to its maximum speed the valve 38 is wide open, and by adjusting the lever 41 any desired speed may be obtained, it being understood that when the valve 38 is closed or partially closed the pressure of the air beneath the piston 17 will 35 force said piston upwardly, and with it the valve 10, and the flow of the steam through the pipe 5 will be partially cut off, and this movement of the piston may be regulated at will by means of the lever 41 of the valve 38, 40 and the operation of the engine may thus be controlled at all times and under all conditions.

The object of the valve 32 is to provide an escape for the air from the lower end of the 50 cylinder under certain conditions of pressure and is particularly adapted to relieve back pressure caused by the momentum of the engine after the steam-supply is cut off.

The water flowing through the chamber 23 55 in the walls of the piston keeps said piston at a proper temperature at all times and prevents the same from becoming heated by conduction from the valve-casing.

My improved governor is simple in construction and operation and perfectly adapted to accomplish the result for which it is in-

tended, and it will be apparent that changes in and modifications of the construction described may be made without departing from the spirit of my invention or sacrificing its 65 advantages.

Having fully described my invention, I claim as new and desire to secure by Letters Patent—

1. In a governor for marine and other engines, the combination of an air-cylinder, a spring-controlled piston mounted therein and means to admit air to said cylinder below said piston, a discharge-pipe communicating with said cylinder beneath said piston, a hand-operated valve mounted in said discharge-pipe, and a supplemental discharge-passage communicating with said cylinder beneath said piston, a supplemental cylinder with which said discharge-passage communicates, 70 a screw-threaded plug mounted in the outer end of said cylinder and adjustable therein, a piston mounted in said cylinder, a piston-rod connected therewith and passing through said adjustable plug, and a spring mounted 75 on said piston-rod between said adjustable plug and said piston, whereby the tension of said spring is regulated by the adjustment of said plug, said cylinder being provided with side-ports or openings, substantially as and 80 for the purpose described.

2. An improved governor for steam-engines, comprising a valve-casing, a sliding valve mounted therein, a cylinder, brace-rods extending between said valve-casing and the 95 cylinder and connected with both of these parts, a spring-controlled piston mounted in said cylinder and connected with the valve, means for supplying air under pressure to the cylinder below said piston, a chamber formed 100 in the walls of the cylinder and extending around the same and an ingress and egress pipe communicating with said chamber, a discharge-pipe projecting from the end of the cylinder below the piston and provided with a 105 hand-operated valve, and a supplemental discharge-passage communicating with the cylinder beneath the piston and provided with a supplementary projecting cylinder inclosing a spring-actuated valve and provided with 110 devices for adjusting said valve and with side ports or openings, substantially as and for the purpose set forth.

In testimony that I claim the foregoing as my invention I have signed my name, in presence of the subscribing witnesses, this 27th day of May, 1897.

EDWIN B. THORBURN.
